WIRELESS SIGNALING APPARATUS.

1,252,520.

Specification of Letters Patent. Patented Jan. 8, 1918.

Application filed April 2, 1915. Serial No. 18,645.

To all whom it may concern:

Be it known that I, Roy A. WEAGANT, a citizen of the United States, residing in the town of Roselle, county of Union, State of New Jersey, have made certain new and useful Improvements in Wireless Signaling Apparatus, of which the following is a specification.

The invention is an improvement on the well-known Fleming valve shown and described in U. S. Letters Patent No. 803684, dated November 7th, 1905. In this improved apparatus shown and described herein, there is employed a vacuum chamber containing a hot element and a cold element and outside the chamber an element is fixed in position, this element has extended capacity area and is in close proximity to the outer surface; the outer element is preferably metal, like copper, arranged with its surface area approximately parallel with the path of electrons moving from the hot element at one end toward the cold element at the other end of the chamber; this outer element is of sufficient area to surround both elements, and the space between said elements; the object being to establish an extensive and intimate relation between the path of electrons and the surface of the outer element. As shown and described herein, the apparatus can be operated to generate groups of oscillations following each other at any desired time interval, which interval may be either within or without the range of audibility. By reason of this action when adjustments are so made that these groups of oscillations follow each other at a rate which is nearly or quite beyond the upper limit of audibility, the device becomes a receiver of continuous or undamped oscillations, due to the fact that the oscillation frequency of these groups may be so adjusted as to be slightly different from that of the incoming signals; the result produced being a beat between these two trains of oscillations, producing an audible note in the telephone receiver of any desired pitch. This result is due to the fact that with the described arrangement, the valve automatically opens and closes the battery circuit at a rate which depends on adjustment of the constants of the circuit, the establishment of the required filament temperature, and the employment of a valve

exhausted to the proper degree. Generally speaking, the vacuum should be such that the application of 100 volts or less between the inclosed terminals will produce a visible blue glow or arc-like effect. The oscillation frequency, however, is controllable by means of the associated oscillation circuit, which includes the well-known tuning elements; that is, adjustable inductance and adjustable capacity, and the electrical association of this circuit with the outer element of the valve.

The utility of the resistance and the capacity shunting the resistance in the battery circuit is that it supplies amplification of the effect of small electrical impulses impressed upon the valve. When this resistance, which is very high, and of the order of that of the valve itself, is employed, an adjustment of the potential of the battery to a point higher than is desirable without the use of this resistance is possible, and we are enabled to get a critical adjustment of the ionization of the gas within the valve, such that the effect of minute electrical disturbances impressed thereon causes the flow of a greatly increased amount of electrical energy through the indicating device and battery circuit, and these variations follow in intensity and rate the variations of the impressed energy.

The resistance contributes materially in attaining the condition of automatic interruption of the battery circuit previously referred to, which enables the valve to operate as a generator of groups of oscillations which have a period determined by the resultant effect of the periodicities of the associated circuits upon one another. The theory of this action appears to be as follows:

When the battery circuit is closed the temperature of the filament being assumed to be correct, the current starts to flow through the battery circuit; as this current builds up, however, a considerable proportion of the impressed electro-motive force is consumed in the resistance outside of the valve with the result that as the current flow through the valve from the battery increases, the potential across the electrodes within the valve decreases and when all conditions are properly adjusted this decrease appears to be of such an extent that the electrical conductivity between two elements of the valve is greatly reduced, so that the circuit, in effect,

opens. This is a theory which explains the operation, but there may be other and different conditions established, not at present fully appreciated.

In the drawing the valve is shown with two local circuits, one of which contains the receiving telephone and the other is associated with the antenna.

- a* is the antenna, *c*¹ a variable condenser, 10 in the antenna, in series with inductance 1, forming a primary of which coil 2 is the secondary; coils 2 and 4 serve as inductances in tuning a local circuit, and are bridged by adjustable condenser *c*⁵. One terminal 11 of this closed oscillating circuit is connected to the outer element *k* of the vacuum valve, the other terminal of said circuit 10, is connected to a point in the second local circuit. The valve is composed of a vacuum chamber 20 *v*, in which is a hot element *f*, in circuit with battery *a*¹ and rheostat *r*¹, and a cold element *p*, both these elements are within the vacuum chamber *v*, outside said chamber arranged parallel with the space separating electrodes 25 *f* and *p*, and closely situated with respect thereto, is an electrode or element *k*, this is preferably cylindrical and spans the space between electrodes *f* and *p* and also laps said electrodes. There is a second local circuit 30 having its terminals connected, respectively to the hot and cold elements *f* and *p* in the valve; in this circuit, in series, is the battery *b*, telephones *t*, and an adjustable capacity *c*⁴ in parallel with telephones *t* and battery 35 *b*; there is in said circuit a high resistance *r*² shunted by a variable capacity *c*³. The resistance *r*² is variable and must be of the order of the normal resistance of the circuit between electrodes *f* and *p*.
- 40 When the elements are arranged as shown and the valve constants are so arranged that the establishment of the blue glow between parts *f* and *p* is imminent, the current in circuit via *b*, *r*², *t*, *f*, *p*, increases, but the 45 increase acts to drop the electro-motive force of battery *b* and circuit opens between *f* and *p*; this circuit is almost immediately re-established, and again broken, and so on continuously. The action results in a successive 50 series of wave trains of high frequency oscillations.

The circuit terminal 10 is shown connected to plate electrode *p* and the second circuit.

What I claim is:

- 55 1. In a wireless signaling apparatus comprising an antenna and an antenna circuit, the combination of a vacuum chamber containing a hot element and a cold element, a conducting terminal having extended area located in position outside said chamber in close proximity to the direct line of movement of the electrons in said chamber, a local circuit connecting the hot and cold elements and including a source of direct current, a resistance, a capacity in parallel with 60 said resistance, an indicating device and means electrically associating said outside element with the antenna.
2. In a wireless signaling apparatus, comprising an antenna and an antenna circuit, 7 the combination of a vacuum chamber containing a hot element and a cold element, a conducting terminal having extended area located in position outside said chamber, in close proximity to the direct line of movement of electrons in said chamber, a local circuit connecting the hot and cold element, including a source of direct current, a resistance, a capacity in parallel with said resistance, an indicating device and a capacity in 8 parallel with said indicating device and source of current, and means for electrically associating said outside element with the antenna.
3. In a wireless signaling apparatus, comprising an antenna and an antenna circuit, the combination with a vacuum valve having a hot element and a cold element within the chamber, an electrostatic control element outside said chamber adapted to project a field of force into the space within the chamber, means associating said outside element with the antenna and a circuit having its terminals connected to the two elements within the chamber, respectively, said circuit including a source of direct current, a resistance, a 9 resistance, a variable capacity in parallel with said resistance and an indicating device.
4. In a wireless signaling apparatus comprising an antenna and an antenna circuit, the combination with a vacuum valve having a hot element and a cold element within the chamber, an element outside said chamber, means associating said element with the antenna, a circuit having terminals connected to the two elements within the chamber, respectively, said circuit including a source of direct current, a resistance, a variable capacity, in parallel with said resistance, an indicating device and a capacity in 10 parallel with said indicating device and current source.
5. In a wireless signaling apparatus, comprising an antenna and an antenna circuit, 11 the combination with a vacuum valve having a hot element and a cold element within the chamber, and electrostatic control element outside said chamber, adapted to project a field of force into the space within the 12 chamber, a coil associated with the antenna circuit, an electrical connection between a terminal of said coil and said outside valve element, an electrical connection between said coil and a point in the battery circuit, 13 said battery circuit having its terminals connected to the two elements within the chamber, respectively, and including a battery, a resistance, and a capacity in parallel with said resistance.

6. In a wireless signaling apparatus, comprising an antenna and an antenna circuit, the combination with a vacuum valve having a hot element and a cold element within the 5 chamber and an electrostatic control element outside said chamber, adapted to project a field of force into the space within the chamber, a coil associated with the antenna circuit, a local circuit, a capacity in said circuit 10 in parallel with said coil, an electrical connection between the terminal of said coil and said outside valve element, an electrical connection between said coil and a point in the battery circuit, said battery circuit having 15 its terminals connected to the two elements within the chamber, respectively, and including a battery, a resistance, and a capacity in parallel with said resistance.
7. A vacuum chamber containing two elements, means for heating one of said elements, a conducting terminal located outside said chamber in close proximity to the direct line of movement of electrons in said chamber, an oscillation circuit having its termi- 20
- nals connected to one of the inside elements 25 and to the outside element, a local circuit having its terminals connected to the inside elements and including a source of direct current and a resistance and a condenser in shunt to each, the resistance having a value 30 of the order of the valve itself, all for the purposes described.
8. In a wireless signaling apparatus, the combination of a vacuum chamber containing two elements, means for heating one of 35 said elements, a local circuit comprising a battery and a non-inductive resistance, each shunted by a condenser, said circuit being connected to said elements and adapted to produce an electron stream between the 40 same, an electrostatic control element outside said chamber, the field of force of outside element being at an angle to the electron stream, and a tuned circuit connected to said outside element and to one of the interior 45 elements, all for the purposes described.

ROY A. WEAGANT.
